UNITED STATES PATENT OFFICE

HERMAN H. SPERTUS AND MAURICE SPERTUS, OF CHICAGO, ILLINOIS

DESIGN FOR A LAMP REFLECTOR

Application filed April 2, 1930. Serial No. 35,108. Term of patent 3½ years.

To all whom it may concern:

Be it known that we, HERMAN H. SPERTUS and MAURICE SPERTUS, citizens of Russia, residing at Chicago, county of Cook, and State of Illinois, have invented a new, original, and ornamental Design for Lamp Reflectors, of which the following is a specification, reference being had to the drawing, forming part thereof.

In this drawing:

Figure 1 is a side elevation of a reflector illustrating our new design,

Figure 2 is a top plan view thereof, and

Figure 3 is a bottom plan view of the same.

We claim:

The ornamental design for a lamp reflector, as shown.

HERMAN H. SPERTUS.
MAURICE SPERTUS.
